PETER W. KRALL, OF CLEVELAND, OHIO.

CONTACT-SLIDE FOR WELDING-MACHINES.

1,360,118.

Specification of Letters Patent. Patented Nov. 23, 1920.

Application filed December 6, 1918. Serial No. 265,520.

To all whom it may concern:

Be it known that I, PETER W. KRALL, a citizen of the United States, and resident of Cleveland, in the county of Cuyahoga and State of Ohio, have invented certain new and useful Improvements in Contact-Slides for Welding Machines; of which I hereby declare the following to be a full, clear, and exact description, such as will enable others skilled in the art to which it appertains to make and use the same.

The invention relates to a sliding contact block for the movable terminal of an A. C. electric welding transformer.

The object of the present invention is to provide a simple, practical and efficient sliding contact block which will be self cleaning, to prevent of accumulation of burnt particles upon the guiding means of the block and which will be adapted to be readily taken apart for cleaning the bearing surfaces.

It is also an object of the invention to provide means adapted to produce between the parts a constant recurring movement which will maintain good bearing and contacting surfaces and thus insure conductivity and prevent turning the sliding parts when a current of high voltage is passed through the device.

With these and other objects in view, the invention consists in the construction and novel combination of parts hereinafter fully described, illustrated in the accompanying drawings and pointed out in the claims hereto appended, it being understood that various changes in the form, proportion, size and minor details of construction, within the scope of the appended claims, may be resorted to without departing from the spirit of the invention or sacrificing any of the advantages thereof.

In the accompanying drawings:—

Figure 1 is a side elevation of a sliding contact block constructed in accordance with this invention;

Fig. 2 is an end elevation of the same;

Fig. 3 is a detail perspective view of the combined dirt guard and scraper; and

Fig. 4 is an elevation of a portion of a welding transformer illustrating the arrangement of the sliding contact block.

In the accompanying drawing, in which like characters of reference designate cor-

responding parts in the several figures, in which is illustrated one embodiment of the invention, the device comprises in its construction a lower stationary member or base A, side members or portions B and an upper slideable contact block or member C which has a limited movement longitudinally of the base or bottom section A. The base or bottom member A has laterally inclined faces A' A' which extend upwardly and inwardly from the side faces of the base or member A and terminate short of the center thereof. The slideable top member or block C is provided at the bottom with inclined faces C' extending upwardly and outwardly from opposite sides of the center of the top block or member to the side faces thereof. The inclined faces B' of the base or member and the inclined faces C' of the top block or member diverge and receive between them the side blocks or members B which are tapered or wedge-shaped to present lower inclined faces B' and upper inclined faces B² to contact with the inclined faces of the top block or member and the base block or member.

The side blocks or members D are yieldably maintained in contact with the inclined faces of the slideable top block and the base block or member by means of springs E mounted upon rods or bolts D piercing the side blocks horizontally equi-distant of the base block and the slideable top block and having a slideable fit to enable the springs E to force the side blocks or members inwardly. The rods or bolts are provided at their outer ends with nuts E' preferably arranged in pairs and adapted to enable the tension of the springs to be readily adjusted to maintain the desired contact between the inclined faces of the top base and side blocks.

The springs maintain a constant frictional contact between the inclined faces and prevent the accumulation of burnt particles and the device operates as a good conductor for the electric current.

The lower block or base, which is stationary, is secured by screws F to the pole piece G and a cooling current of water is passed through the looped opening H in the stationary base block or member.

The slideable upper block or member C has a limited sliding movement upon the

inclined upper surfaces D^2 of the side blocks or members B, B and this movement produces the perfect bearing surfaces without air spaces, and does not interfere with the flow of the electric current through the device, and the device permits a current to flow through it without forming an arc and without turning the parts and welding them together. The constant movement of the parts on each other will wear the bearing surfaces smooth and maintain perfect contact between the blocks or members.

In order to limit the movement of the ¹⁵ ¹⁰ ¹⁵ ²⁰ ²⁵ ³⁰ ³⁵ ⁴⁰ ⁴⁵ ⁵⁰ ⁵⁵ ⁶⁰ ⁶⁵ ⁷⁰ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ ¹⁴⁰ ¹⁴⁵ ¹⁵⁰ ¹⁵⁵ ¹⁶⁰ ¹⁶⁵ ¹⁷⁰ ¹⁷⁵ ¹⁸⁰ ¹⁸⁵ ¹⁹⁰ ¹⁹⁵ ²⁰⁰ ²⁰⁵ ²¹⁰ ²¹⁵ ²²⁰ ²²⁵
